WILLIAM KENYON, JR., OF STEUBENVILLE, OHIO, ASSIGNOR TO HIMSELF
AND HENRY K. KENYON.

Letters Patent No. 74,697, dated February 18, 1868.

IMPROVEMENT IN PIPE-TONGS.

The Schedule referred to in these Letters Patent and making part of the same.

TO ALL WHOM IT MAY CONCERN:

Be it known that I, WILLIAM KENYON, Jr., of Steubenville, in the county of Jefferson, and State of Ohio, have invented a new and useful Improvement in Pipe-Tongs; and I do hereby declare the following to be a full, clear, and exact description thereof, reference being had to the accompanying drawing, making a part of this specification, in which—

Figures 1, 2, and 3 are side views of my improved pipe-tongs, and illustrative of their operation in gripping pipe of different diameters; and

Figure 4 is a perspective view of the same.

Like letters of reference indicate like parts in each.

My invention consists in constructing a pipe-wrench or gas-tongs of a swinging head or jaw, having two operative faces forming about a right angle at their point of union, in combination with a cam-head at the extremity of the handle of the wrench, of such eccentric shape, and so pivoted to the jaw (or the jaw to it) as that the wrench will grasp pipes or cylinders of different diameters, and that the point of contact of the cam with the article grasped shall be in or near a right line passing from the pivot of the cam-head to the angle of the faces of the jaw, and through the centre of the cylinder, no matter what may be the diameter of the cylinder held in the tongs.

To enable others skilled in the art to construct my improved pipe-tongs, I will proceed to explain my invention more fully with reference to the accompanying drawings.

The use of a hooked jaw, attached by a pivot to a wrench having a straight or even slightly curved face, is a well-known device in the construction of pipe-tongs, and I do not wish to be understood as claiming such devices in themselves considered. The peculiar feature of my improvement consists in the angular shape of the loose jaw, which gives a bearing on two different points of the circumference of the cylinder to be grasped, and the peculiar curve given to the cam-head of wrench, in relation to its centre or pivot on which the loose jaw is hung, which curve is such that no matter how far the wrench may be open, the point of contact, and pressure of the cam against the face of the pipe or cylinder in its grasp shall not only be opposite to both the faces of the jaw, but shall lie in or near to the right line passing from the pivot of the jaw through the centre of the cylinder or pipe. By this means not only is the pipe or cylinder held firmly, but the pressure on the pipe or cylinder bears in all directions, from the three points of its contact with the wrench towards the centre of the pipe or cylinder. All the force applied to the wrench operates simply to grasp and hold it, whereas in pipe-wrenches of any ordinary construction, this effect is produced only on a cylindrical body of a particular diameter to which the wrench is specially adapted, while on pipes or cylinders of either larger or smaller diameter, the pressure of the head of the wrench not being properly directed, has a tendency to crush the pipe, or makes it more liable to slip away from the wrench as it presses it either inwards or outwards.

In the drawing, *b* is the handle of the wrench or tongs, the upper end or head of which is enlarged so as to form a cam, the size of which depends on the range or diameter of pipe which the tongs are designed to grasp, and the shape and eccentricity of its curve is regulated as hereinafter described. A hook or jaw, *d*, which may be made of two pieces riveted together at *c*, (as seen in fig. 4,) is pivoted to the neck of the eccentric-head *a* at *c*, as near to the curved face of the head *a* as the strength of the material will admit. The inner faces of the jaw or hook *d* are two, of which one, *s*, may be curved, and the other, *s'*, straight. These faces *s* *s'* are inclined towards each other, so as to meet and form an angle at *t*, the most suitable angle being about ninety degrees. The curve of the eccentric-head *a* depends on the relative position of the pivot *e*, by which the jaw *d* is attached to the head, and the angle *t* of the hook or jaw; this curve being such that the distance from the pivot *e* to the extremity *x'* of the head *a* is nearly equal to the distance from the pivot *e* to the angle *t* of the jaw, (so as to enable the wrench to grasp the smallest diameter of pipe or cylinder;) and the distance from the pivot *e* to the neck *v* of the wrench-head *a* is the smallest possible, (so as to enable the wrench to grasp cylinders or pipe of a diameter nearly equal to the distance from *e* to *t*;) and the length of radii from the pivot *e* to the circumference of the eccentric-head *a* is gradually diminished from *e* *x'*, the largest radius, to *e* *v*, the smallest

radius. The effect of such a construction and position of the curved head, is, that in whatever position the hook d may be placed relatively to the head a , if a right line be drawn, (as the dotted line in figs. 1 to 3,) from the pivot c to the angle t of the hook, such right line (which indicates the direction of pressure of the cam-head a on the pipe or cylinder e held in the grasp of the tongs,) will pass through or near to the centre of such pipe or cylinder. Usually I slot or bifurcate the hook d throughout nearly or quite its whole extent, and allow the head a , or so much thereof as may be necessary, to play in such slot or bifurcation; or, as shown in the drawing, I make the hook d of two parts, d' d'' , (fig. 4,) the parts or halves operating on opposite sides of the head a , and connected therewith, and with each other, by one or more rivets c and posts c' . The working-faces of either hook or head, or of both, may, and one of them should, be slightly serrated or roughened, so as to enable the jaws a and d to hold a secure bite or grasp, when applied to a smooth cylindrical object for the purposes named.

The devices described are very simple of operation. The pipe e to be turned, or held against turning, is encompassed by or grasped between the head a and jaw d . A firm gripe is secured by a slight backward force exerted by the handle b on the rivet c , though but little such force, if any, will generally be required. The tongs should be placed on the pipe e with the open side of the jaw d on the side toward which the handle b is to be turned in order to turn the pipe, or toward which the force is to be exerted, if it be desired to hold the pipe against turning.

While not limiting myself to the exact shape of the hook d shown in the drawing, I find it better, in order to adapt my tongs for use with pipe of different sizes, to make the inner face of the hook d with one curved face s , and one straight face s' , the object being, by the use of such a jaw and eccentric-head a , to get three bearing-surfaces against the face of the pipe, each pressing towards the centre of the pipe or cylinder, no matter what may be the diameter of the pipe grasped by the tongs, as shown in figs. 1 to 3, and such construction of hook I claim as my invention.

If desirable, the shape of the devices described may be varied by making a double or bifurcated head a , and hinging between its divided halves a single hook, d . The mode of operation would remain the same.

I claim, in addition to the advantages before stated, that my gas-tongs are simpler and cheaper in construction than those in ordinary use; also that they are lighter and more durable; that they are self-adjusting, and are adapted without alteration and adjustment to being used with pipe of varied sizes, so much so that a single pair of tongs so constructed, will enable a plumber to joint and unjoint, with equal ease and rapidity, any and all sizes and diameters of gas-pipe in ordinary use. The tongs described are also useful for catching circular bolt-heads, cylindrical rods or bars, and other similar objects.

Having described my improvement, what I claim as my invention, and desire to secure by Letters Patent, is—
The combination of the bifurcated movable jaw d , with the eccentric cam-head a , at the end of the handle of a pipe-wrench, constructed and arranged substantially as hereinbefore described.

In testimony whereof, I, the said WILLIAM KENYON, Jr., have hereunto set my hand.

WILLIAM KENYON, JR.
